UNITED STATES PATENT OFFICE.

FRANZ LAUBACH, OF OAK PARK, ILLINOIS, ASSIGNOR TO LYON & HEALY, OF CHICAGO, ILLINOIS, A CORPORATION OF ILLINOIS.

TRACKER-BOARD.

1,317,201.

Specification of Letters Patent. Patented Sept. 30, 1919.

Application filed February 2, 1916. Serial No. 75,821.

To all whom it may concern:

Be it known that I, FRANZ LAUBACH, a citizen of the United States, residing at Oak Park, in the county of Cook and State of Illinois, have invented new and useful Improvements in Tracker-Boards, of which the following is a specification.

The invention relates to a tracker board for player pianos, and more particularly to 10 the class of automatically adjustable double tracker boards for this type of musical instruments.

The primary object of the invention is the provision of a tracker board of this character wherein with the use of a peculiar form 15 of perforated music sheet the player piano will be played mechanically when the sheet travels in either direction over said tracker board, which is automatically controlled for 20 this purpose, thereby enabling the playing of one or more selections of music during the winding and unwinding of the music roll, the player action being either electrically or mechanically actuated.

Another object of the invention is the provision of a tracker board of this character wherein the continuous playing of the instrument may be had by the use of a single 25 perforated music roll on the winding and rewinding of the same, the tracker board being of novel form and is automatically controlled, thereby obviating the necessity of 30 constantly changing the music roll after the single winding thereof.

A further object of the invention is the provision of a tracker board of this character wherein the usual wear and tear upon 35 a music roll is reduced to a minimum, and a longer selection or selections of music may be played by the use of a single roll without increasing the length of the perforated sheet.

A still further object of the invention is the provision of a tracker board of this character which is extremely simple in construction, thoroughly reliable in operation, and inexpensive in manufacture and installation.

Other objects will be in part obvious and in part hereinafter pointed out.

The invention accordingly consists in the 40 features of construction, combination of elements and arrangement of parts which will be exemplified in the following construction,

and the scope of the application of which will be indicated in the appended claims.

In the drawings:—

55

Figure 1 is a fragmentary front elevation of a tracker board constructed in accordance with the invention.

Fig. 2 is an enlarged sectional view on the line 2—2 of Fig. 1.

60

Fig. 3 is a plan view with the front track-er bar removed.

Fig. 4 is a sectional view on the line 4—4 of Fig. 3, showing the front tracker bar in place.

65

Fig. 5 is a fragmentary plan view of a music sheet for use with the tracker board construction.

Fig. 6 is a fragmentary view showing the connections to the tracker board.

70

Similar reference characters indicate cor-responding parts throughout the several views in the drawings.

The operation of the pneumatically oper-ated piano is so well known as not to require 75 illustration or description here, as the pneu-matics and the operation form no part of the present invention. However, it is to be understood that the tracker board construc-tion is to be installed in either the mechani-cally or automatically operated player piano, 80 or the electrically operated type.

In carrying the invention into practice there is employed the usual spool frame or 85 boxing 10 which is mounted within the piano in the ordinary well-known manner, and has journaled therein the lower winding and upper rewinding spools 11 and 12, respec-tively, which are located at opposite sides of the tracker and are operatively connected 90 with the pneumatic motor of the player action, the connections being such that the rewinding reel will travel at the proper speed, and these connections may be of any approved form and are not allied with the 95 construction of the tracker board forming the subject matter of the present invention and hereinafter fully described.

As heretofore stated, the tracker is ar-ranged between the reels 11 and 12 and sup-ported within the frame or boxing 10 there-for, and comprises a horizontal bar 13 hav-ing an independent series of horizontally dispo-sed ducts 14 and 15, respectively, which

are located on opposite sides of the center of the said bar, these ducts of each series being closely arranged and are eighty-eight in number corresponding to the number of 5 notes of the piano action, and have connected thereto tubes 16 which lead to the pneumatics, (not shown), of the player action. The connections to the pneumatics are such that corresponding notes of the two sections 10 are adjacent the juncture of the two sections, as clearly shown in Fig. 6.

Formed on the front face of the bar 13 are spaced parallel guide cleats 17, and secured in any suitable manner to these cleats 15 is a front tracker bar 18, which is also provided with independent series of ducts 19 and 20, respectively, corresponding in number to the respective ducts 14 and 15 for communication therewith, and over this 20 tracker bar 18 is adapted to travel the perforated music sheet 21, which is constructed with independent series of perforations 22 and 23, respectively, arranged in inverse order so that a selection or selections of music 25 can be played mechanically by the player piano on the winding or rewinding of the music roll in a manner presently described.

Arranged between the guide cleats 17 between the bars 13 and 18 of the tracker 30 is a switch rail or slide 24 which is provided with the independent series of ducts 25 and 26, respectively, the ducts 25 of one series being designed to register with the ducts 14 and 19 in the respective bars 13 and 35 18 when the ducts 26 are out of registration with the ducts 15 and 20 of the said respective bars, and vice versa, according to the direction of travel of the perforated music sheet 21 so that a particular selection of 40 music can be continuously played both on the winding and the rewinding of the music roll, or any given number of selections of music can be played during the reverse travel of the music sheet, the switch rail or 45 slide being automatically shifted in the tracker in a manner presently described.

Located without the frame or boxing 10 at opposite sides thereof are pneumatics 27 which have their movable members 28 ex-

tended into the path of terminal projections 50 29 on opposite ends of the rail or slide, and leading to each of these pneumatics from the main bellows of the player action is a tube 30, these pneumatics being each alternately thrown into communication with 55 the main bellows of the player action in any suitable manner as by means of a perforation at each end of the music sheet and a corresponding passage at each end of the tracker board, so that the said pneumatics 60 will be actuated at each end of the music sheet for the shifting of the switch rail or slide 24 for alternately closing the respective series of perforations in the tracker according to the direction of travel of the 65 music sheet thereover so that the piano will be automatically played on the winding and rewinding of the perforated music sheet, the said music sheet being alternately wound upon the reel 11 from the reel 12, and re-wound upon the latter from the said reel 11 during the automatic playing of the piano, and during the travel of the perforated music sheet over the tracker the instrument will be continuously played both on the 70 winding and rewinding of the music sheet, the tracker being automatically controlled from the pneumatics 27 which are actuated by the main bellows of the player action.

From the foregoing description, taken in 80 connection with the accompanying drawings, the construction and manner of operation of the device will be clearly understood, and therefore a more extended explanation has been omitted.

What is claimed is:—

A tracker-board having independent series of ducts connected with the pneumatics of a player action, a slide in the said tracker for alternately closing each of the independent series of ducts, and pneumatic means for actuating said slide. 90

In testimony whereof I affix my signature in presence of two witnesses.

FRANZ LAUBACH.
